UNITED STATES PATENT OFFICE.

ALEXANDER CALDWELL, OF NEW YORK, N. Y., ASSIGNOR TO HIMSELF AND EDWARD W. BILL, COMPRISING THE FIRM OF BILL AND CALDWELL, OF NEW YORK, N. Y.

HAT.

SPECIFICATION forming part of Letters Patent No. 690,230, dated December 31, 1901.

Application filed September 20, 1901. Serial No. 75,781. (No model.)

To all whom it may concern:

Be it known that I, ALEXANDER CALDWELL, a citizen of the United States, residing at New York, in the county of New York and State of New York, have invented certain new and useful Improvements in Hats, of which the following is a full and complete specification, such as will enable those skilled in the art to which it appertains to make and use the same.

10 This invention relates to hats, particularly to straw hats; and it has for its object to provide means for rendering an ordinary straw hat or an especially-flexible straw hat sufficiently stiff of brim and permanent of angular contour, while not impairing its general adaptability to the head.

The invention is in general an improvement upon the straw hat patented June 25, 1901, No. 677,324, by Edward W. Bill and myself 20 as assignees of Edward Ferraby Walsh, which embodies a certain self-conforming straw hat which when placed upon the head will adapt itself to the contour thereof.

25 My present invention, which is much simpler in construction and possesses advantages thereover, consists in the novel construction and arrangement of parts hereinafter described and claimed.

In the accompanying drawings, forming 30 part of this specification, in which like letters of reference designate corresponding parts, Figure 1 is a central vertical section of a hat embodying my invention. Fig. 2 is a perspective view of a portion of the hat with the upper layer of the brim removed. Fig. 3 is 35 an enlarged plan view of one of the stiffening devices removed, and Fig. 4 is an edge view or elevation thereof.

In the practice of my invention I construct 40 a hat of plaited or other straw in the usual manner to form the crown A and the brim B. In the type of hat shown in the drawings, to which my invention is chiefly and most advantageously applicable, the brim is flat or horizontal and the upper surface of the crown 45 lies upon a plane parallel with the brim. Usually such hats are stiffened by means of a sizing or like application; but according to my present invention I only thus stiffen the upper portion of the crown of the hat, leaving the lower portion of the crown unstiffened, and the brim B, which is usually made of two

superposed layers of plaited straw stiffened by sizing, I likewise leave unstiffened.

Between the brim or upper layer B and the under layer B', I secure stiffening devices C, embodying my present invention. These stiffening devices C have the form of polygonal plates of thin metal, preferably triangular in form and formed with a peripheral border of perforations D, through which they may be sewed to the under layer of the brim. It is not essential, however, that the devices be thus secured, as they may be fastened in any desired manner. By making the devices 55 triangular they may be retained in great measure by their own shape, since inward movement thereof would be prevented by contact of their inclined edges with any of the usual threads which secure the two layers of 60 the brim together.

Upon the point or inner end of the main body is secured or formed an extension or rod E, which projects upwardly from the inner edge or apex of the triangle at right angles thereto. The length of the main body or perpendicular of its triangle is approximately equal to the width of the brim, and the extension or rod E lies in contact with the lower portion of the crown. As shown in the 75 drawings, it is preferable to insert the point of the extension or rod E through the straw of the crown, so that it extends practically through the vertical center thereof. It is within the limits of my invention to have the 80 extensions located wholly on the inside of the crown to be covered by the sweat-band or to insert them through the brim upon the outside of the crown to be covered by the usual band-ribbon. The expedient shown is preferred and also operates to fix the devices in 85 position and prevent movement thereof.

After the stiffening devices have been secured between the two brim layers and their extensions connected to the crown the hat is 90 stiffened upon the upper portion of its crown by the usual sizing and is blocked, trimmed, and finished.

Since the lower portion of the hat and the brim are unstiffened by the usual sizing, they 100 will conform to the shape of the head of the wearer, permitting the hat to elongate or widen or conform to the exact contour desired, according to the shape of the head,

yet in virtue of the metallic stiffening-pieces C and their extensions E the brim B will be stiff and unbendable, will not curl, warp, corrugate, or incline upwardly or downwardly 5 from the horizontal, and the lower portion of the crown, to which the extensions or rods are secured, will not bend inwardly or collapse, bulge, or protrude, notwithstanding its flexibility and conformability; but as the 10 stiffening-plates C are separate and individual the circumferential pliability of the brim is not impaired, and the slenderness of the extensions or rods prevents their interfering with the flexibility of the crown, while the 15 triangular shape of the strips E permits the greatest possible elongation or widening of the junction of crown and the brim, which constitutes the area of pressure-contact of the hat upon the head in hats of this character, 20 and yet at the same time there is formed at the outer circumference of the brim practically a continuous stiffening, preventing any portion of the brim from bending upwardly or downwardly.

25 Having thus fully described my invention, what I claim as new, and desire to secure by Letters Patent, is—

1. A straw hat provided with a plurality of 30 separate and independent stiffening devices comprising polygonal plates arranged around and within the brim of the hat and having their outer edges closely adjacent whereby to form a positive and approximately continuous stiffening for the brim to prevent 35 bending of its edge.

2. A straw hat provided with a plurality of 40 separate and independent stiffening devices comprising polygonal plates arranged around and within the brim of the hat and having their outer edges closely adjacent whereby to form a positive and approximately continuous stiffening for the brim to prevent bending of its edge, and provided with upwardly-projecting extensions adapted to contact with 45 the crown of the hat.

3. A straw hat provided with a plurality of 50 separate and independent stiffening devices comprising polygonal metallic plates arranged around and within the brim of the hat, and having their outer edges closely adjacent whereby to form a positive and approximately continuous stiffening for the brim to prevent bending of its edge, and provided with upwardly-projecting extensions 55 adapted to contact with the crown of the hat.

4. A straw hat provided with a plurality of 60 stiffening devices comprising flat plates arranged around and within the brim of the hat with their outer edges substantially in contact, and relatively slender or narrow vertical extensions projecting upwardly from the inner edges of the said plates and contacting with the crown of the hat.

5. A straw hat provided with a plurality of 65 stiffening devices arranged around and within its brim and comprising plates widened at the outer ends and narrowing near the crown of the hat.

6. A straw hat provided with a plurality of 70 stiffening devices arranged around and within said brim and comprising flat polygonal plates of metal connected at their outer ends and narrowing near the crown of the hat, and rods secured upon the upper faces of the said plates at their inner ends.

7. A straw hat provided with a plurality of 75 stiffening devices arranged around and within its brim and comprising plates widened at the outer ends and narrowing near the crown of the hat and provided with narrow extensions or rods projecting at right angles thereto and secured to the said crown.

8. A straw hat provided with a plurality of 80 stiffening devices arranged around and within its brim and comprising triangular plates disposed with their apexes inwardly and provided therewith upwardly-projecting extensions to contact with the crown of the hat.

9. A straw hat having its brim and the lower portion of its crown unstiffened and flexible 85 and composed of superposed layers, and a plurality of stiffening devices arranged around the said brim and between the layers and secured thereto, and comprising flat triangular metallic plates arranged with their widest 90 ends at the outer periphery of the brim and substantially in contact with one another, and provided at their apexes with upwardly-directed relatively narrow extensions or rods ranging at right angles thereto and secured 95 to the crown of the hat.

In testimony that I claim the foregoing as my invention I have signed my name, in presence of the subscribing witnesses, this 17th day of September, 1901.

ALEXANDER CALDWELL.
